The ornamental design for a warmer for disposable towels, as shown and described.

DESCRIPTION

FIG. 1 is a top, front, and right side perspective of a warmer for disposable towels showing my new design, the power cord being shown broken-away to indicate indeterminate length;

FIG. 2 is a front end elevational view thereof;

FIG. 3 is a rear end elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a top plan view thereof in the open condition.

FIG.1.

FIG. 2.

FIG. 3.

FIG. 4.

FIG. 5.

FIG. 6.

FIG. 7.

FIG. 8.
